(57) **CLAIM**

The ornamental design for an electrode connector, as shown and described.

DESCRIPTION

FIG. 1 is a top perspective view of an electrode connector, showing our new design;

FIG. 2 is a top plan view thereof;

FIG. 3 is a bottom plan view thereof;

FIG. 4 is a side elevational view thereof, the opposite side elevational view being identical;

FIG. 5 is a front elevational view thereof; and,

FIG. 6 is a rear elevational view thereof.

The broken line showing in FIGS. 1-5 is for illustrative purposes only and forms no part of the claimed design.
